UNITED STATES PATENT OFFICE.

LORENZO T. YODER, OF PITTSBURGH, PENNSYLVANIA.

CHILD'S PLAYHOUSE.

1,078,027.

Specification of Letters Patent.

Patented Nov. 11, 1913.

Application filed January 26, 1912, Serial No. 673,551. Renewed May 14, 1913. Serial No. 767,721.

To all whom it may concern:

Be it known that I, LORENZO T. YODER, a citizen of the United States, residing at Pittsburgh, in the county of Allegheny and State of Pennsylvania, have invented new and useful Improvements in Children's Playhouses, of which the following is a specification.

My invention relates to play-houses for children, and its object is to provide a portable rectangular structure which has three walls, preferably a front and two ends and which may have its open rear side against a vertical wall or other fixed vertical structure so as to form a rectangular play-room or house. The portable walls may be readily assembled and taken apart. They are each made of a light vertical wooden frame-work covered with figured oil-cloth or paper and provided with a suitable door or doors and windows.

Referring to the accompanying drawings, Figure 1 is a perspective view of my invention applied to a wall, the frame-work being in part provided with a covering or siding. Fig. 2 is a section showing the manner of applying the top corner-blocks which lock the tops of the ends to the sides and at the same time provide an ornamental finish. Fig. 3 is a bottom view of a corner-block. Fig. 4 is a section on the line IV—IV, Fig. 1; and Fig. 5, a section on the line V—V, Fig. 4.

On the drawings, 1 designates the front frame-work, and 2 and 3, the end frames. The front frame has the horizontal strip 4 and the top horizontal strip 5, these strips being connected at their ends to the vertical corner strips 6 by screws or nails. The strips 4, 5, and 6 are narrow and form a light vertical rectangular figure to support the other parts of the front frame-work 1. To one of the corner strips 6, I connect the wooden door frame 7 which has its lower end just above the strip 4 and its upper end just below the horizontal strips 8 secured to the corner strips 6.

9 is a vertical strip secured to the strips 4, 5, and 8 so as to form a casing for the free vertical edge of the door-frame 12. Between the strip 9 and the end 3 I provide the two spaced vertical strips 10 which are secured to the strips 4, 5, and 8.

11 is a horizontal strip secured to the right-hand strip 6 and the strips 9 and 10.

The ends of the window-frame 12 are

connected to the strips 10, and the bottom to the strip 11. The window-frame has strips 13 arranged to form rectangular spaces resembling real windows. The frame 60 1 and the door-frame 7 are covered with any suitable material 14, in imitation of the exterior of a house, but I have found oil-cloth figured to represent brick or tile to be satisfactory.

The end frame-work 2 is of light wood also and has the horizontal bottom strip 4^a and the horizontal top strip 5^a connected at their ends by the vertical corner strips 6^a. One corner strip 6^a is connected by light removable fastening, such as screws, to the left-hand corner strip 6. The corner strips 6 and 6^a are all of the same height so that the strips 5 and 5^a may be at the same level. The adjacent ends of the strips 5 and 5^a, and, consequently, of the frame-works 1 and 2 are held in their proper angular relation and prevented from separating by means of the corner block or key 15 which rests on the corner formed by the meeting of the front and end frame-works 1 and 2 and has in its lower edge or bottom an L-shaped groove 16 adapted to fit over, or receive the upper edges of the said strips 5 and 5^a at their meeting angle.

18 is a block fitting in the angle between the lower ends of the front and end frames. The block has the metal strips 19 provided with down-turned flanges 20 which interlock with the upturned flanges 22 on the metal strips 21 secured to the lower ends of the corner strips 6 and 6^a. I have not shown the right-hand corner provided with a corner-block 18, but it may be understood to have one. It will be seen that the block 18 95 with the interlocking strips 19 and 21 holds the bottoms of the frames tightly together and at the desired angular relation.

The horizontal strips 8 and 11^a are connected to the corner strips 6^a. The window-frame 12^a is connected to the strips 8^a and 11^a and provided with the cross-strips 13^a.

The light wooden frame-work 3 has the strips 4^b, 5^b, 6^b, 8^b, and 11^b constructed and assembled like the respective strips 4^a, 5^a, 6^a, 8^a, and 11^a. The front edge of this frame-work is connected to the right-hand end of the front frame-work 1 just as the frame-works 1 and 2 are connected, 15^b representing the corner-block or key connecting the 110 frame-works 1 and 3.

17 represents a fixed wall against which

the open rear side of the play-house is placed, the rear strips 6^a and 6^b being in contact with, or close to, the said wall 17. The wall 17 may be the interior side-wall of the nursery or other room in the home of the children. In summer the play-house may be placed out of doors against the fence, or the side of the house or other building.

10 It is seen that I have provided a play-house which can be readily assembled and taken apart, quickly moved from place to place, and be set up against a wall, fence, or the like where children may arrange their furniture and toys to suit their fancy.

I claim—

15 In a children's play-house, a vertical front frame, a vertical end frame abutting

the front edge of the middle frame and making an angle therewith, a corner block 20 fitting the meeting angle between the lower ends of the frames, metal strips secured to the corner block and having each a horizontal flange parallel with the sides of the said angle, and spaced from and lying opposite to the edges of the block, and a metal strip secured to the bottom of each frame and having a flange lying between the adjacent corner block and the corresponding flange secured to the said block. 25

Signed at Pittsburgh, Pa., this 23rd day of January, A. D. 1912.

LORENZO T. YODER.
